UNITED STATES PATENT OFFICE.

FRANCIS H. CAMPBELL, OF FLUSHING, NEW YORK, ASSIGNOR TO MERGENTHALER LINOTYPE COMPANY, A CORPORATION OF NEW YORK.

TYPOGRAPHICAL MACHINE.

1,165,069.

Specification of Letters Patent. Patented Dec. 21, 1915.

Application filed January 30, 1915. Serial No. 5,165.

To all whom it may concern:

Be it known that I, FRANCIS H. CAMPBELL, a citizen of the United States, residing at Flushing, in the county of Queens and State of New York, have invented certain new and useful Improvements in Typographical Machines, of which the following is a specification, reference being had therein to the accompanying drawing.

10 My invention has reference to typographical casting machines, such for instance as linotype machines, wherein a slug or bar is cast in a slotted mold against a composed line of matrices, which is presented temporarily in front thereof and serves to form the type characters on the edge of the slug. The mold employed in such machines usually comprises cap and body portions, constituting the upper and lower walls of the mold 15 slot, and two intermediate elements or liners, constituting the end walls thereof. It is frequently necessary to change the size of the mold in order to produce slugs of different lengths; and this result is usually secured by removing one of the liners and substituting another of a width corresponding to the new length required. The liner commonly employed is somewhat similar to that shown in U. S. Letters Patent to G. A. Bates, 20 No. 618,554, and is of such construction that it may be withdrawn forwardly from the mold without requiring the removal of any other of the parts.

In practice some difficulty is experienced 25 in effecting the removal of the liner, due to its tendency to adhere to the cap and body and to their pressure thereon. In some instances, the operators or machinists resort to the use of a screw driver or other hard 30 tool, which method often results in serious injury to the liner or the mold parts. It also happens that sometimes the liner is so badly mutilated as to cause burs or fins to be formed thereon, and so as to prevent the 35 mold cap from seating firmly in place.

It is the object of my present invention to avoid the necessity for these objectionable methods, and to that end I provide suitable 40 means whereby the liner may be easily and instantly removed when required. In the present instance, such means comprise a movable ejector arranged on a fixed rear support and adapted to engage the liner and 45 push it forwardly out of the mold.

In the accompanying drawing, I have 55 shown my invention as applied merely by way of example and in preferred form, and obviously many changes and variations may be made therein without departing from its spirit. I therefore desire it to be understood that I do not limit myself to any specific form or embodiment, except in so far as such limitations are specified in the claims.

Referring to the drawing: Figure 1 is a 60 perspective view, partly broken away, of a portion of a linotype machine having my invention applied thereto; and Fig. 2 is a sectional detail thereof.

One or more molds A are mounted in the 70 mold wheel B, which is journaled upon the arm C extending laterally from the mold slide (not shown), all in the customary manner. The mold comprises as usual the body portion A², the cap portion A¹, and 75 the intermediate liners A³ and A⁴, providing between them a longitudinal slot open at the front and rear wherein the slug is cast, the slot during the casting action being closed at its front by an assembled line of matrices 80 presented momentarily to the mold, and closed at its rear by the mouth of the casting pot from which the molten metal is forced into the mold. The liner A³ is formed on its under side with a transverse rib A⁵ to engage in a corresponding groove in the body portion A², which construction of the parts 85 allows the liner to be withdrawn forwardly from the mold and then replaced by another of different size.

As before stated, the resistance offered by the liner often causes considerable trouble in effecting its removal by hand, and I therefore provide mechanical means whereby this operation may be effected speedily and without difficulty. In the form shown, these means comprise an ejector E slidably supported on the arm C and formed with elongated slots E¹, which embrace studs C¹ secured to said arm, the studs serving to guide 100 the ejector and also to limit its movement in opposite directions. At its forward end, the ejector is formed with a reduced portion E² which is adapted to engage the rib A⁵ and travel in the transverse groove in the 105 body portion A² during the ejection of the liner and thus avoid injurious contact with the other parts. The ejector is held nor-

mally in its rearmost or inactive position by a spring D, and is moved forwardly against the action of the spring by a lever F pivoted at F¹ to the arm C and connected to the 5 ejector by a pin-and-slot connection E². The lever F is also formed with an upstanding handle F² to facilitate its operation by the attendant or machinist.

The operation of the device will be apparent. When a liner is to be removed it is simply necessary to rotate the wheel B to locate the mold with its liner A³ in position to be engaged by the ejector E, this position of the parts being shown in Fig. 1. The ejector is then moved forwardly by the lever F and pushes the liner before it out of the mold, the reduced portion E² passing freely between the cap and body portions, as shown by full lines in Fig. 1 and by dotted lines 20 in Fig. 2. When the liner is thus removed, the lever F is released by the operator and the spring D returns the parts to their original position.

Having thus described my invention, its 25 construction and mode of operation, what I claim and desire to secure by Letters Patent of the United States, is as follows:

1. In a typographical casting machine, the combination of a longitudinally slotted 30 mold open at the front and rear and including a removable element which determines the size of the mold slot, and means mounted in the machine and operable to effect the removal of said mold element when required.

35 2. In a typographical casting machine, the combination of a longitudinally slotted mold including a removable element which constitutes one of the end walls of the mold slot, and an ejector mounted upon a fixed support and movable at will to effect the removal of the mold element.

40 3. In a typographical machine, the combination of a mold including a removable element, a movable ejector mounted upon a fixed support and adapted to effect the removal of said element, and a carrier for the mold to present it in coöperative relation to the other casting devices and movable to lo-

cate it with its removable element in position to be engaged by the ejector. 50

4. In a typographical casting machine, the combination with a longitudinally slotted mold, comprising the cap portion A¹, the body portion A², and the intermediate liner A³ constituting one of the end walls of 55 the mold slot and formed with the transverse rib A⁵ to engage in a corresponding groove in the body portion, of the movable ejector E arranged upon a fixed support and adapted to engage the liner and push it forwardly from the mold. 60

5. In a typographical machine, the combination of a mold including a removable element, a movable carrier to present the mold in coöperative relation to the other casting devices, and means for effecting the removal of said mold element, said means comprising the ejector E slidably mounted upon a fixed support, and the pivoted lever F for operating the ejector. 70

6. In a typographical casting machine, the combination with a mold, comprising cap and body portions and an intermediate removable liner, of an ejector movable between the cap and body portions to effect 75 the removal of said liner, the said ejector being reduced at its active end so as to facilitate its passage between the cap and body portions of the mold in its ejecting action.

7. In a typographical machine, the combination of a mold including a removable element, a movable carrier to present the mold in coöperative relation to the other casting devices, a movable ejector, a spring to hold the ejector in its normal or inactive position 85 out of the path of the movement of the mold carrier, and a device for moving the ejector against the action of the spring to effect the removal of the mold element. 80

In testimony whereof, I have affixed my 90 signature in presence of two witnesses.

FRANCIS H. CAMPBELL.
